(57) **CLAIM**

The ornamental design for an LED lighting unit, as shown and described.

DESCRIPTION

FIG. 1 is a front, top, and right-side view of an LED lighting unit that has the design.

FIG. 2 is a back elevation view of the LED lighting unit.

FIG. 3 is a left elevation view of the LED lighting unit.

FIG. 4 is a top plan view of the LED lighting unit.

FIG. 5 is a right elevation view of the LED lighting unit.

FIG. 6 is a front elevation view of the LED lighting unit.

FIG. 7 is a bottom plan view of the LED lighting unit.

FIG. 8 is a front, top, and right-side view of an LED lighting unit that has a second embodiment of the design.

FIG. 9 is a back elevation view of the LED lighting unit.

FIG. 10 is a left elevation view of the LED lighting unit.

FIG. 11 is a top plan view of the LED lighting unit.

FIG. 12 is a right elevation view of the LED lighting unit.

FIG. 13 is a front elevation view of the LED lighting unit; and, FIG. 14 is a bottom plan view of the LED lighting unit.

1 Claim, 6 Drawing Sheets
